AUTOMATIC TEA MAKER

John P. Theisen, Jacksonville, Ill., assignor to New York
Shipbuilding Corporation, New York, N. Y., a corpo-
ration of New York

Application September 9, 1954, Serial No. 32,228

Term of patent 14 years

(Cl. D44—26)

To all whom it may concern:

Be it known that I, John P. Theisen, a citizen of the United States, residing at Jacksonville, in the county of Morgan and State of Illinois, have invented a new, original, and ornamental Design for Automatic Tea Maker, of which the following is a specification, reference being had to the accompanying drawing, forming a part thereof.

In the drawings:

Figure 1 is a side elevational view of an automatic tea maker showing my new design;

Figure 2 is a top plan view thereof;

Figure 3 is an elevational view of the side opposite that shown in Figure 1;

Figure 4 is a front elevational view thereof; Figure 5 is a rear elevational view thereof; and Figure 6 is a bottom plan view thereof.

I claim:

The ornamental design for an automatic tea maker, substantially as shown.
